PAPER HANDLING APPARATUS

Harry A. Crisp, Appleton, Wis., assignor to The Appleton Coated Paper Company, Appleton, Wis., a corporation of Wisconsin

Application January 17, 1931. Serial No. 509,462

12 Claims. (Cl. 242—56)

The invention relates to paper handling apparatus and more particularly to an apparatus for the winding, cutting and delivery of paper in roll form.

5 The general object of the invention is to provide a machine in which the spindles for the paper are automatically fed into the machine in which the paper is automatically wound from a supply roll on to each spindle in succession to 10 form the paper roll of a predetermined footage or length and is measured and cut off to this length and after the winding operation, the completed roll is delivered from the machine automatically, thereby greatly decreasing the cost of 15 handling and preparing the paper for shipment or subsequent use over methods heretofore used.

The invention further consists in the several features hereinafter set forth and more particularly defined by claims at the conclusion hereof.

20 In the drawings, Fig. 1 is a side elevation view of an apparatus embodying the invention, parts being broken away and parts being shown in section;

Fig. 2 is a view partly in side elevation and 25 partly in transverse section, taken along the broken line 2—2 of Fig. 6, with parts also broken away and shown in section;

Fig. 3 is a detail sectional view taken along the line 3—3 of Fig. 2;

30 Fig. 4 is a detail sectional view taken on the line 4—4 of Fig. 2, parts being shown in section and parts being broken away;

Fig. 5 is a detail view of the return-feed weight;

Fig. 6 is a detail sectional view taken along the 35 line 6—6 of Fig. 2;

Fig. 7 is a detail sectional view taken along the line 7—7 of Fig. 2;

Fig. 8 is a detail vertical sectional view through 40 the machine taken generally along the line 8—8 of Fig. 11;

Fig. 9 is a detail transverse sectional view through the machine looking toward the fixed knife;

Fig. 10 is a detail sectional view taken on the 45 line 10—10 of Fig. 1;

Fig. 11 is a detail plan view of the spindle feed and pasting mechanism, parts being shown in section and parts being broken away.

The machine in general comprises winding 50 mechanism, means for automatically feeding spindles for the paper successively to said winding mechanism, means for automatically applying paste to said spindles as they pass to said winding mechanism, mechanism for controlling 55 the extent of the winding of the paper by the

winding mechanism on the spindles from a paper supply roll, this control mechanism acting to operate a cutter to sever the wound-up paper from the incoming sheet, this mechanism also acting in conjunction with the wound-up roll of 60 paper to control an ejector by which the finished roll of paper is moved to position for delivery from the machine.

Referring first to Fig. 1, the numeral 15 designates the incoming end of a sheet of paper from 65 a paper supply roll, the same passing over guide rollers 16 and 17 suitably journaled in the framework 18 of the machine, thence over a roll 19 mounted on a rotatable shaft 20, thence over a winding roll 21 driven through a shaft 22 and 70 cooperating with a companion winding roll 23 which is free to be rotated under the action of the spindle and the paper being wound up thereon.

Each spindle comprises a mandrel 24 usually 75 of metal and a winding core 25 that may be of either metal, paper or other suitable material and in most instances is paper. The empty spindles are deposited in a magazine 26 formed of suitably braced angle frame or track members 27 upon 80 which the outer ends of the spindles are free to roll, the magazine being inclined to permit the spindles to feed by gravity along the tracks formed by the angle members 27 to a position for their delivery into the winding zone which is between 85 the rolls 23 and 21, one of the spindles being shown in a position for the commencement of the winding operation. The shaft 22 rotates continuously and carries a sprocket 28 connected by a chain 29 to a sprocket 30 mounted to revolve on 90 a fixed shaft 31 and pinned to a clutch drum 32 as shown in Fig. 6, this drum rotating continuously and through a control hereinafter described, the drum 32 is adapted to be connected in driving relation with a cam 33 also rotatable on the shaft 95 31. This cam 33 as shown in Fig. 2 is engaged by a roller 34 carried by a link 35 connected by a pivot pin 36 to a block 37 secured to one of a pair of spaced lever members 38 pivoted on a shaft 39 carried by the framework of the machine, said 100 lever members 38 being connected together by a transverse tie member 79. These lever members 38 thus receive motion under conditions hereinafter described from the cam 33, and their outer end portions 40 are bent downwardly and carry a shaft 40' on which a roller 41 is mounted and adapted to engage the paper as it is rolled up on the spindle, then presented to the winding mechanism. Thus the levers 38 receive motion both 105 110

from the paper being wound and the control cam 33.

Referring to Figs. 1, 8 and 11, the foremost spindle in the magazine is adapted to be engaged at its outer ends by spaced gate or stile wheels 42 mounted on a shaft 43 extended above and across the magazine and carrying a ratchet wheel 44 engaged by a pawl 45, pivoted at 46, and held in operative position by a spring 47, it being noted that the release of this pawl will, through the weight of the spindles in the magazine, cause the stile wheels 42 to rotate and thus through the control of the pawl 45 allow the lowermost spindle in the magazine to be released therefrom and proceed down the trough or tracks 27 to a winding position.

Control of the pawl 45 is effected through a release pawl 48, pivotally mounted at 49 on a bracket 50, secured to the block 37, and normally urged against a stop pin 51 by a spring 52, the free end of the pawl 48 acting under the control of the link 35 and levers 38, after these parts have reached an upper position, to engage the free end of the pawl 45 on the downward movement of these parts to release said pawl 45 from the ratchet 44 and permit said ratchet to turn one tooth and thus release a single spindle, this action taking place at a time when the winding mechanism will be in a condition to operate on the newly released spindle.

In order to hold the initial windings of paper on the spindle, means have been provided to apply paste to the spindle on its way to the winding mechanism. Referring to Figs. 8 and 11 of the drawings, it will be noted that there is a roller engaging finger 53 on a shaft 54 extending across the magazine below the gatewheels 42, said shaft having a crank arm 55 at one end, limited in one position by a stop pin 56 and engageable with a crank arm 57 mounted on a paste arm shaft 58 and held in engagement with the arm 55 by means of a spring 59. The shaft 58 has arms 60 secured thereto and carrying a paste applying bar 61 adapted to be moved by the arms into a paste tank 62, disposed below the spindle tracks 27, with the paste bar 61 disposed in the path of movement of the spindles so that when a spindle, released by the gates 42, passes over the finger 53, its weight will depress the same and thereby swing the arm 55 toward the left thus moving the shaft 58 through the movement of the arm 57 by the arm 55 so as to dip the paste bar 61 in the paste tank and as spindle leaves the finger 53, the paste bar 61 will be raised up against the spindle as it passes by through the action of the spring 59 on the arm 57 of the paste applying mechanism just described so that the core 25 of the spindle has paste applied thereto over a certain portion of its area and is delivered in this condition to the feeding zone.

When a spindle is in a feeding position, its pasted portion comes into contact with the end 63 of the paper 15 coming from the supply roll and thereby becomes pasted to this end of the paper and at this time the winding of the paper on the spindle also commences since the weight of the spindle is such as to cause the paper 15 to be fed between it and the rotating roll 21 and consequently the paper is fed into the machine at the same time the spindle is revolved and in revolving imparts its turning movement to the companion winding roll 23. The paper thus winds up on the spindle until the desired amount is obtained which is determined by mechanism hereinafter described that controls the cutting mech-

anism. As the paper winds up, the arms 40 of the levers 38 are raised and in raising, they in turn operate the ejecting mechanism, which when the desired amount of paper is wound on the roll, allows the finished roll to roll off of it and down onto the spaced guides of a delivery trough 64. This ejector mechanism comprises spaced ejector members 65 having feet 66 with inturned spindle engaging ends 67 as seen in Figs. 8 and 10. These ejector members are vertically slidably mounted in a frame member 68 carried on upright posts 69 secured to the main side frame 18 of the machine. This frame member 68 has spaced stops 71 and 72 secured to it. These spaced stops cooperate with a stop pawl or lever 73 pivotally mounted at 74 on an arm 75 of a dog member 76 secured to the upper end of each ejector member 65. Each stop member 71 is formed as a side projection of a channel bar 77 and each channel bar 77 forms a seat for a compression spring 78 that acts through the dog 76 to cushion the end portion of the downward stroke of the ejectors 65. The actuating or control levers 38 have a transversely extending bar 79 secured thereto supporting spaced sets of fixed members 80 and 81, each member 81 having a finger 82 cooperating with a latch 83, slidably mounted in the arms of its companion member 81 and spring pressed outwardly by a spring 84, to engage the dog 76 and thus raise the dog together with the ejector member 65 operatively connected thereto as the fingers 82 and latches 83 are raised through the upward movement of the levers 38. The latches or levers 73 are urged to latched position by springs 73' and are pivotally connected at 85 with trip arms 86 adapted to be engaged by the fingers 82 when moving downwardly from a raised position, as the dotted line position shown in Fig. 8. These trip members 86 each rest on a supporting stud 87 secured to the companion dog 76. With this construction, when the spindle is in position to start the winding operations, the ejector mechanism is in position shown in full line in Fig. 8 under which conditions the levers or latches 73 engage with their lower stops 72 and the springs 78 are under such compression as is imposed by the weight of the levers 38, the parts being held in this position through the weights of the parts including the arms 38 that are resting on the spindle and connect through the fingers 82 and latches 83 to the dogs 76, secured to the ejector members 65. As the winding operation proceeds, the paper builds up on the spindle and hence pushes or raises the levers 38 upwardly, this action also causing a corresponding upward movement of the fingers 82 and latches 83 and consequently a raising movement of the dogs 76 and the ejectors 65 secured thereto. This movement finally moves the latches 73 into cooperative relation with the stops 71 when the ejector mechanism is in its extreme upper position as shown in dotted lines in Fig. 8. Under these conditions, the wound up roll, which has been cut from the web, has been elevated by the feet 66 of the ejector members to a position where the spindles will readily roll off of the same and down into a delivery trough 64. As the members 38 return downwardly to their initial position, the fingers 82 which have passed by the trip levers 86 on their upstroke, engage said levers at the beginning of their downstroke, as shown in the dotted line position of Fig. 8, and act to push the trip fingers 86 to the left and thereby swing the latches 73 out of locking engagement with the stop 71 150

so that the ejectors may descend to their initial position ready to receive the next spindle.

When the fingers 82 have passed the trips 86 on their downward movement, the latches 83 have also passed the dogs 76 due to the beveled face ends of the dogs and the latches which permit the retraction of the latches 83 against the action of the springs 84 so that the parts again assume the full line position shown in Fig. 8.

10 The cutting mechanism consists of a relatively fixed knife member 88 here shown in the form of a rod in Fig. 9 clamped to laterally adjustable brackets 89 mounted between the frame members 70 and collars 90 on the posts 69, this rod adapted to be tensioned through the action of set screws 92 passing through the hubs or collar portions 93 of the brackets 89 and engageable with the posts 69. This rod 88 carries an apron member 94 acting to insure the positioning of the 20 severed end of the paper sheet adjacent the roll for purposes hereinafter described. The movable cutter consists of a segmentally formed knife bar 95 adapted to slide over the surface of the winding roll 21 and having side flanges 96 engageable with the ends of said roll and a grooved edge, the upper edge 97 of which is a cutting edge, said knife being operated through connecting rods 98, each connected at one end to it and at its 25 other end to lever arm 99 and a shaft 100 of the measuring control mechanism.

30 Referring to Figs. 1 to 7 inclusive, the measuring control mechanism includes spaced side frame members 101 secured together and to one of the main frames of the machine by the shaft 31 and frame bars 102, these parts having shouldered threaded ends and clamping nuts 103 thereon to establish this relation and the shaft 100 which is shown in Fig. 4 journaled in one of the frame members 70 and which is similarly journaled in the other main side frame member has an extension extending through one of the frame members 101 and carrying a crank arm 104 operatively connected by a link 105 to one arm of a lever 106 which is pivotally mounted on a pin 107 carried by the actuating link 35 and has an inclined nose 106' adapted to be engaged by a cam member 108 secured to the cam 33 and movable therewith, so that as said cam 108 makes one revolution, when clutched to the drum 32, the outer end 45 of the lever 106, as viewed in Figs. 1 and 2, will swing downwardly and through link 105, arm 104, shaft 100, swing the arms 99 upwardly and thus through the rods 98 move the cutter knife 95 into cutting relation with the fixed knife 88 and thus sever the sheet as it is being wound up 50 on the roll, it being noted that the sheet in passing to the spindle passes across the face of the knife or cutting block 88. A spring 104' acts on the arm 104 to return the cutter and its operating mechanism to retracted position.

55 Attention has been called to the fact that the roll 21 rotates all the time. Consequently, after the paper from the supply roll is pasted onto the spindle between the winding rolls 21 and 23 the paper will continue to wind thereon until cut off by the cutting mechanism above described. Consequently upon the timing of the operation of the cutting mechanism will depend the amount of paper wound up on the spindle and this timing is effected by the time the cams 33 and 108 are rotated by the shaft drum 32 through a clutch connection therewith. Referring to Figs. 2, 4 and 6, this clutch connection includes a clutch pawl 109 pivotally mounted on a stud 110 secured 65 to the side of the cam 33, said pawl having a

rear flat face 111 adapted to abut against a corresponding face 112 on the hub of said cam so as to limit its movement in release position and carrying a spring 113 engageable with the hub of the cam tending to move it to clutched position which is effected between said pawl and drum 32 by the cramping engagement of the sides of recess 114 in the pawl with the flange of the drum 32. This movement to clutched position is controlled by a stop 115 which normally engages the pawl 109 to hold it in release position and which is mounted on a shift bar 116 slidably mounted in guide slots in the frame members 101 and normally held in this position by a spring 116' and a stop pin 117 but which is shifted to release the pawl by the movement of a timing or measuring control member 118 into operative engagement with a stop 119 secured to said bar 116.

70 Referring to Figs. 2 to 6 it will be noted that the control member 118 has its hub 120 slidably splined by suitable screws 121 to a keyway 122 in a guide shaft 123 mounted to oscillate in the frame members 101 and that the upper end of said member is recessed and threaded to form a 75 half nut 124 which is adapted to engage or be released from a feed screw shaft 125 journalled in the frame members 101. This screw shaft 125 depends for its rotation upon the feed of the paper from the supply roll to the winding mechanism and for this purpose the roll 19 over which the paper passes has a sprocket wheel 126 secured to its shaft 20, as shown in Fig. 1 and is connected by a chain 127 to a sprocket 128 on a stud shaft 129, said sprocket 128 being com- 80

85 pounded with a gear 130 meshing with a gear 131 fixed to the feed shaft 125. From the above it will be apparent that, as the clutch control member 118 is moved by the rotation of the feed screw 125 and moves along the shaft 123 a projecting finger 132 on said member comes into engagement with the stop 119 and thereby moves the bar 116 to the left as viewed in Fig. 4, until the stop 115 moves out from under the pawl 109 to permit the same to be moved to clutched 90 position. The member 118 normally has its nut portion 124 held in engagement with the shaft 125 by a spring 133 connected at one end to the frame and at the other to a pin arm 134 connected to the shaft 123 to which the member 118 is keyed, see Fig. 1, and said member is returned, when out of contact with the shaft 125, by a weight 135, Fig. 5 connected by a cord 136, Fig. 4, to one of the screws 121. 95

100 The measuring of the paper being wound up 100 on the roll is effected by the length of movement of the control member 118 along the screw shaft 125 and this is controlled by a suitable means under the control of the operator, as shown in Figs. 2, 6 and 7. This means includes a fixed 105 block 137 and a series of manually settable blocks 138, these blocks being mounted between spaced guides 139 and 140, the blocks 138 each carrying a thumb screw 141 working in a slot 142 in the upper guide 139 and adapted to be clamped 110 against said guide to hold each block in an operative or inoperative position to form a track of 115 variable length. In order that the blocks 138 can only be moved to inoperative position in successive order, each of these blocks has a tongue 120 or stop 143 engageable with the next succeeding block in the series so the first block then in contact with a stop finger 144 on control member 118 has to be pushed back to inoperative position 125 before the next one in series can be. The guide 130

139 is grooved at 145 to allow the stop finger 144 to pass along the tops of the blocks when the member 118 is fed forward by the screw 125 until the stop passes the fixed block 137 at which time it comes in contact with a spring finger or cam 146, Figs. 6 and 7, which acts thereon to depress said finger 144 and thus rock the member 118 and shaft 123 toward the right as viewed in Fig. 2 and against the tension of the spring 133 to move the nut portion 124 out of engagement with shaft 125 and at the same time tilt finger 144 to a position beneath the lower bevelled faces 147 of the blocks 137 and 138 so that the weight 135 will return the member 118 to its initial position behind the last of the series of blocks 138. When it reaches this position, the spring 133 again swings the control member 118 to an operating position. If now the most remote of the blocks 138 shown in Fig. 6 is released from its operating position and pushed out of the way of the finger 144 it is obvious that the return feed of the member 118 will terminate sooner and consequently the forward feed will be shorter so that a shorter interval of time will elapse before the clutch pawl 109 is again operated and that removal of the other blocks 138 in successive order will cut down this time until the shortest feed interval is reached which is that across the block 137 that determines the minimum length of paper to be wound on each spindle for each operating cycle of the machine.

Referring to Fig. 2 it will be noted that the roller 34 carried by the link 35 rides on the upper part of the cam 33 and that the lower end 148 of said link is slotted so that said link may be reciprocated either by said cam or by the oscillatory movement of the levers 38. After the end of the paper that has been wound up on a spindle is cut from the supply web 15 by the knife 95, the severed end of the web will be loose on the roll 21 and the feed of the paper will be stopped under these conditions, the severed end however being held adjacent the roll 21 by the apron 94 at this time. However, before the next spindle is allowed to assume an operative position between the winding rolls 21 and 23, it is necessary to bring the severed end 63 of the paper web to a position where it will be engaged by the pasted portion of the next spindle to be delivered to the winding mechanism and for this purpose means have been provided associated with the ejector mechanism for securing the necessary feeding traction of the paper web against the roll 21 and this means is shown in Figs. 1 and 10. One of the ejector members 65 has a pawl 149 pivotally mounted at one end 150 to the lower end thereof as shown in Fig. 1 and just before said member 65 reaches its lowermost position, this pawl 149 engages a projection 151 on a pivoted member 152 to swing the same downwardly. This member 152 and a companion member 153, are both pivotally mounted on a pin 154 and a compression spring 155 interposed between them allows relative swinging movement between them and transmits motion from the member 152 to member 153. The member 153 is connected by a link 156 to a crank arm 157 on a transversely disposed shaft 158 journalled in the side frame members of the machine and a series of arms 159 are secured at spaced intervals to said shaft 158 and carry paper engaging rollers 160 which are positioned for movement into cooperative relation with the paper and the drum 21 just below the apron 94. Thus when the end of the pawl 149 engages the projection 151 and swings the member 152 down-

wardly, this motion is transmitted through spring 155, member 153, link 156, crank arm 157, shaft 158, arms 159 to swing the rollers 160 on said last named arms into paper feeding position and the severed end 63 is thus fed to a position where it will be pasted to the spindle delivered to the winding mechanism, the pawl 149 finally tripping past the projection 151 as shown in Fig. 1 and being limited in its inward release position movement when the members 65 are raised, by a stop pin 161 on the member 152.

The component parts of the machine having been described in detail a brief general operation of the machine will be given. It has been noted that the cam 33 controls the reciprocating movement of the levers 38 to actuate the spindle feed and the ejector mechanism and that the cam 108 associated with the cam 33 controls the cutting mechanism and that the time of actuation of both these cams is controlled by the measuring mechanism which actuates the clutch which drives the above named cams. Assuming that a spindle has been delivered to the winding mechanism and paper has been wound thereon to such an extent that for the given set position of the blocks 138, the control member 118 has been moved by the screw shaft 125 to a position to engage the stop 119, shift bar 116 and hence allow pawl 109 to engage the drum 32, then the cam 33 is revolved and as it moves from the lower position shown in Fig. 2, it acts through the link 35 and levers 38 to raise the ejector members 65 from the position they have assumed through the raising of said levers 38 under the action of the paper that has been wound up on the roll and just before the ejector members 65 reach their uppermost position the paper which is then tensioned between the spindle and the roll 21 across the face of the fixed knife 88 is then cut by the knife 95 under the action of the cam 108 and directly thereafter the cam 33 lifts the levers 38 to their uppermost position and consequently through the parts 83, 82 and 76 lift the ejector members 65 to their uppermost position and the completed roll of paper is then rolled off the ends 67 of the feet 66 and into the delivery trough 64. During the upward movement of the levers 38, the pawl 48 snaps by the pawl 45 and as the levers 38 move down under the control of the cam 33, the pawl 48 releases pawl 45 and allows the gate wheels 44 to turn to release a new spindle and at the same time the ejector members 65 move down to a position for the next cycle of operations on this spindle and actuate the rollers 160 to bring the web into position to receive the new spindle with the paste supplied thereto when said spindle takes its position between the winding rolls. After the clutch has been engaged to cause these operations to take place, the control member 118 under the action of the cam 146 and weight 135 has been moved back to release the shifter bar 116 and hence bring it to position to cause stop 115 to release the pawl 109 as the cam 33 completes its revolution and said control member 118 is then carried back to a point where its finger 144 drops behind the last operatively positioned block 138 to again allow the nut portion 124 of said member 118 to be fed by the screw shaft 125 to a clutch engaging position which occurs as the paper wound up on the last presented spindle between the said spindle and the rolls 23 and 28 reaches the desired length and is ready for cutting off and ejection from the machine.

The extent of travel of the control member 150

- 118 along the screw shaft 125 before operating the clutch part 109 is determined by the blocks 137 and 138, the amount of paper wound up on a spindle presented to the winding mechanism is also dependent upon this extent of travel or time interval necessary to effect this travel and consequently the removal of one or more of the blocks 138 will lessen this travel and hence the time between the cutting off and feeding in 10 operations. It will of course be understood that as soon as the spindle is in position between the winding rolls the feed of the paper thereto commences so that while the member 118 is on its return stroke out of contact with the screw 15 shaft 125 a certain amount of paper is being wound onto the spindle.
- From the foregoing it will be noted that I have provided a paper handling apparatus in which the paper web or sheet from a supply roll 20 is automatically fed to the winding mechanism and wound upon a spindle automatically delivered from a magazine to receive it and that when a roll of predetermined length has been formed, the web is severed and the finished roll is delivered out of the machine.
- I desire it to be understood that this invention is not to be limited to any particular form or arrangement of parts except in so far as such limitations are included in the claims.
- 30 What I claim as my invention is:
1. In a paper handling apparatus, the combination of paper winding mechanism, means for delivering a spindle to said mechanism with adhesive applied thereto, means for feeding paper in web form to said winding mechanism for winding up on said spindle by said mechanism, means for cutting the paper on the spindle from the web, and means controlled and actuated by the wound roll for delivering the finished roll 35 of paper from the apparatus.
  2. In a paper handling apparatus, the combination of paper winding mechanism, a spindle magazine, means for releasing spindles from said magazine one at a time in succession and delivering them to the winding mechanism, means under the control of the spindle for applying the adhesive to the spindle as it passes from the magazine to said winding mechanism, means for feeding paper in web form to said winding 40 mechanism for winding up on said spindle by said mechanism, means for cutting the paper wound on each spindle from the web, and means for delivering the finished wound rolls of paper from the apparatus.
  - 55 3. In a paper handling apparatus, the combination of paper winding mechanism, means for delivering a spindle to said mechanism with adhesive applied thereto, means for feeding paper in web form to said spindle for winding thereon by said winding mechanism, means for cutting the paper on said spindle from the web, means for delivering the finished roll of paper from the apparatus, and timing mechanism actuated and controlled by the feed of paper to said 60 winding mechanism for determining the effective period of operation thereof and hence the amount of paper wound up on the spindle.
  4. In a paper handling apparatus, the combination with mechanism for winding paper from 70 a supply web upon a spindle, of means for cutting the paper thus wound from the web, drive means for said cutting means including clutch and control means for said clutch including a screw shaft driven by the feed of the paper to said winding mechanism, a clutch control mem-
- ber engageable with said shaft and moved thereby, and settable means under the control of the operator for determining the position of engagement of said control member with said shaft.
5. In a paper handling apparatus, the combination with mechanism for winding paper from a supply web upon a spindle, of means for cutting the paper thus wound from the web, drive means for said cutting means including a clutch and control means for said clutch including a screw shaft driven by the feed of the paper to said winding mechanism, a clutch control member engageable with said shaft and moved thereby, and means including a series of adjustable blocks forming a track of varying length for said control member for determining the position of engagement of said control member with said shaft.
6. In a paper handling apparatus, the combination with a mechanism for winding paper from a supply web upon a spindle, of means for cutting the paper thus wound from the web, drive means for said cutting means including a clutch, and control means for said clutch including a screw shaft driven by the feed of the paper to said winding mechanism, a clutch control member engageable with said shaft and moved thereby, and means including a series of adjustable blocks forming a track of varying length for said control member for determining the position of engagement of said control member with said shaft, said adjustable blocks being provided with stops to prevent shortening of the track except by a successive movement to inoperative position of said blocks.
7. In a paper handling apparatus, the combination of a pair of spaced winding rolls adapted to cooperate with a spindle positioned between them and a web of paper led over one of said rolls to wind the paper on to the spindle, a magazine for the spindles, an inclined track for delivering the spindles successively to operative position relative to said winding mechanism, means for releasing the spindles one at the time from the magazine to said track, adhesive applying means set in the path of the spindle as it moves down said track and controlled by the spindle to apply adhesive to said spindle before it assumes a winding position, means for driving one of said rolls to operate said winding mechanism and the feed of paper thereto, means for cutting the web from the roll of paper wound on the spindle after a predetermined interval, and means for delivering the finished roll of paper from the apparatus.
8. In a paper handling apparatus, the combination with mechanism for winding paper from a supply web upon a spindle to a predetermined length, of means for cutting the paper thus wound from the web, and an ejector mechanism for raising the finished roll of paper on its spindle to a discharge position, said ejector mechanism operating to tension that portion of the web between the roll and the winding mechanism during the operation of the cutting means.
9. In a paper handling apparatus, the combination of a pair of spaced winding rolls adapted to cooperate with a spindle positioned therebetween and a web of paper led over one of said rolls to wind the paper onto the spindle, means for driving the roll over which the paper passes on its way to the spindle, means for feeding the spindle into winding position between the rolls, means for cutting off the paper on the roll from the web of paper after a predetermined amount

has been wound on said spindle, and means for ejecting the finished roll from the winding mechanism comprising a pair of spaced spindle engaging ejector members, and means for reciprocating said ejector members in cyclic sequence with said spindle feeding means and said paper cutting means.

10. In a paper handling apparatus, the combination with mechanism for winding paper from a supply web upon a spindle, means for cutting the paper thus wound from the web, ejector mechanism including ejector members engageable with the spindle, and ejector operating mechanism engageable with the paper wound on the spindle and moved thereby and hence moving said ejector members during the winding operation.

11. In a paper handling apparatus, the combination with mechanism for winding paper from a supply web upon a spindle, means for cutting the paper thus wound from the web, ejector mechanism including ejector members engageable with the spindle, and ejector operating mechanism engageable with the paper wound on the spindle and moved thereby and hence mov-

ing said ejector members during the winding operation, and other means operable at the termination of the winding operation upon said ejector to move the same to a position for discharge of the roll of paper on the spindle from the apparatus. 80

12. In a paper handling apparatus, the combination of a mechanism for winding paper from a supply web upon a spindle, including spaced rolls between which the spindle is supported, one of which rolls is driven and forms the feeding roll for the web, means for cutting the web after a predetermined length of paper has been wound upon the spindle, means for delivering the spindle with the roll of paper thereon from the machine, means for delivering another spindle to the winding mechanism with adhesive applied thereto, and means, controlled by said first named delivery mechanism, for advancing the severed end of the web on said feeding roll in a position to be engaged by the adhesively coated portion of said spindle as the same is delivered to a position between the winding rolls. 85 90 95
